UNITED STATES PATENT OFFICE.

ALBERT J. BENNETT, OF CHICAGO, ILLINOIS.

COMB CLEANER.

Application filed December 5, 1921. Serial No. 519,825.

To all whom it may concern:

Be it known that I, ALBERT J. BENNETT, a citizen of the United States of America, and a resident of Chicago, county of Cook, and State of Illinois, have invented certain new and useful Improvements in Comb Cleaners, of which the following is a specification.

My invention relates to devices for cleaning combs, and has for its object the production of a superior device for this purpose.

In the accompanying drawings—

Fig. 1 is a perspective view; and

Fig. 2 is a longitudinal section with intermediate parts broken away.

The general shape of the device is like that of a violin bow, in which the frame is represented by wire, and the horse hair by thread, preferably linen.

The frame, with its handle, is a continuous piece of wire bent into the form shown, and having its ends covered or inclosed by a sleeve 5 which forms the extreme end of the handle. From this sleeve, the branches 6 and 7 form the handle and extend thru another sleeve 8, from which point they diverge to form the horizontal portions 9 and 10. These portions are then bent downward to form the vertical members 11 and 12 which are connected thru horizontal members 13 and 14 with other vertical members 15 and 16. A horizontal part 17 connects 15 and 16, and corresponds to the parts 9 and 10.

Connected to the upper parts of the uprights 11 and 12 is a bridge 18 having its ends 19 and 20 bent around parts 11 and 12. The upper edge of the bridge is in the form of a comb having teeth 21 which are bent slightly over the parts 9 and 10 as shown in Fig. 2. On the uprights 15 and 16 is another bridge 22 having teeth 23 similarly bent over the horizontal wire 17.

The bridges 18 and 22 are secured to their uprights by having their ends grasp those uprights with sufficient tightness to maintain said bridges in position. However, the bending of the teeth over the horizontal wires while the grasping ends are under those wires, serves to lock said bridges in place.

It will be observed that the members 11,

13 and 15 form a broad U, and that the members 12, 14 and 16 form another broad U parallel to the first one. The bridges 18 and 22 are on the inside of the vertical legs of these U's, with the result that when the teeth of the bridges are bent over the ties connecting the U's, said teeth are inclined from each other.

On the teeth 21 and 23 is a continuous thread 24, one end of which is connected to tooth 26, and the other end of which is connected to tooth 25. This thread is wound upon the teeth by hand, or may be so wound. In carrying the thread from tooth 25 to and around the corresponding tooth in comb 23, and then back around the tooth adjacent to 25, there is a slight tension on the thread which tends to stretch it and also to draw the opposite legs of the U's toward each other. For the first few laps of thread back and forth around teeth 21 and 23, this deflection of the legs of the U's is inappreciable in amount, but by the time there are twenty or thirty laps on the teeth, the deflection is enough to make the frame into a spring which keeps the thread taut after the end has been secured to tooth 26. As the thread is simply looped on the teeth, any inequalities in tension which occur during winding are equalized by the slipping of the thread on the teeth when the device is used. The outward incline of teeth 21 and 23 maintains the loops of the thread at the bottom of the teeth.

What I claim is:

1. In a device of the class described, a frame and a handle therefor formed of a continuous piece of wire having its ends in the handle, the central part of which piece of wire forms a horizontal member 17, from the ends of which the wire extends in two branches to form two U-shaped members, from the other ends of which U's the wires are brought together to form another horizontal member corresponding to the first one mentioned, a connection securing the branches of wire together at this junction, the branches extending from this connection to form the handle, bridges connecting the upper ends of the U's and serving to reinforce the frame at the points where the U's merge into the horizontal members, said bridges

having teeth on their upper edges, and thread mounted upon said teeth and given tension by the U's of the frame.

2. In a device of the class described, a frame consisting of two U-shaped members formed of continuous wire so bent that the upper ends of corresponding legs of the U's are connected together by horizontal mem-

bers integral with the U's, the wire of one of which horizontal members extends laterally to form a handle, bridges reinforcing said wire at the four corners where the U's connect to the horizontal members and thread carried by said bridges. 10

ALBERT J. BENNETT.
